(57) **CLAIM**

The ornamental design for a cleaning cart, as shown and described.

DESCRIPTION

FIG. 1 is a front, right, top perspective view of a cleaning cart, showing my new design;

FIG. 2 is a rear, left, bottom perspective view thereof;
FIG. 3 is a front elevational view of the reduced scale thereof;

FIG. 4 is a rear elevational view of the reduced scale thereof;
FIG. 5 is a left side view of the enlarged scale thereof;
FIG. 6 is a right side view of the enlarged scale thereof;
FIG. 7 is a top plan view of the enlarged scale thereof;
FIG. 8 is a bottom plan view of the enlarged scale thereof;
FIG. 9 is an enlarged view of detail 9 in FIG. 1;
FIG. 10 is an enlarged view of detail 10 in FIG. 1;
FIG. 11 is an enlarged view of detail 11 in FIG. 1;
FIG. 12 is an enlarged view of detail 12 in FIG. 1;
FIG. 13 is an enlarged view of detail 13 in FIG. 2;
FIG. 14 is an enlarged view of detail 14 in FIG. 2;
FIG. 15 is an enlarged view of detail 15 in FIG. 2;
FIG. 16 is an enlarged view of detail 16 in FIG. 2;
FIG. 17 is an enlarged view of detail 17 in FIG. 3;
FIG. 18 is an enlarged view of detail 18 in FIG. 3;
FIG. 19 is an enlarged view of detail 19 in FIG. 3;
FIG. 20 is an enlarged view of detail 20 in FIG. 3;
FIG. 21 is an enlarged view of detail 21 in FIG. 3;
FIG. 22 is an enlarged view of detail 22 in FIG. 5;
FIG. 23 is an enlarged view of detail 23 in FIG. 5;
FIG. 24 is an enlarged view of detail 24 in FIG. 6;
FIG. 25 is an enlarged view of detail 25 in FIG. 6;
FIG. 26 is an enlarged view of detail 26 in FIG. 6;
FIG. 27 is an enlarged view of detail 27 in FIG. 7;
FIG. 28 is an enlarged view of detail 28 in FIG. 7;
FIG. 29 is an enlarged view of detail 29 in FIG. 7;
FIG. 30 is an enlarged view of detail 30 in FIG. 8;
FIG. 31 is a front, right, top perspective view of the cleaning cart in an alternate configuration;

FIG. 32 is a front, right, top perspective view of the cleaning cart in an alternate configuration;

FIG. 33 is an enlarged view of detail 33 in FIG. 31;

FIG. 34 is an enlarged view of detail 34 in FIG. 31;

FIG. 35 is an enlarged view of detail 35 in FIG. 32; and,

FIG. 36 is an enlarged view of detail 36 in FIG. 32.

The dashed broken lines in the figures are for the purposes of illustrating portions of the cleaning cart and form no part of the claimed design.

The short-short-long dashed broken lines immediately adjacent to the claimed areas in the views represent the boundaries of the design and form no part of the claimed design.

(Continued)

The dash-dot-dash broken lines are for notating enlarged views and form no part of the claimed design.
